US0D1015013S

(12) **United States Design Patent** (10) **Patent No.:** **US D1,015,013 S**
(45) **Date of Patent:** **** Feb. 20, 2024**

(54) **COVER**

- (71) Applicant: **NOOKOLOGY LLC**, Hoboken, NJ (US)
(72) Inventors: **Brian J. Gellman**, Hoboken, NJ (US); **Marc Gellman**, Miami Beach, FL (US)
(73) Assignee: **Nookology LLC**, Hoboken, NJ (US)
(**) Term: **15 Years**
(21) Appl. No.: **29/897,501**
(22) Filed: **Jul. 14, 2023**

Related U.S. Application Data

- (62) Division of application No. 29/884,570, filed on Feb. 13, 2023, now Pat. No. Des. 999,552.
(51) **LOC (14) Cl.** **06-04**
(52) **U.S. Cl.** USPC **D6/528**; D6/534; D6/527

(57) **CLAIM**

The ornamental design for a cover, as shown and described.

DESCRIPTION

FIG. 1 is a front right side perspective view of a cover having the cover in an open position;
FIG. 2 is a rear left side perspective view of FIG. 1;
FIG. 3 is a front view of FIG. 1;
FIG. 4 is a rear view of FIG. 1;
FIG. 5 is a left side view of FIG. 1;
FIG. 6 is a right side view of FIG. 1;
FIG. 7 is a top view of FIG. 1;
FIG. 8 is a bottom view of FIG. 1;
FIG. 9 is a front right side perspective view of FIG. 1 having the cover in a closed position;
FIG. 10 is a top front left side perspective view of FIG. 1 having a manual toothbrush inserted and the cover in another closed position;
FIG. 11 is a top front left side perspective view of FIG. 1 having an electric toothbrush head inserted and the cover in another closed position;
FIG. 12 is a view of FIG. 10 shown in use on a sink ledge for environmental context; and,
FIG. 13 is a view of FIG. 11 shown in use on a sink ledge for environmental context.
Broken lines are used to illustrate portions of the cover and other broken lines illustrate environmental subject matter that form no part of the claimed design.

1 Claim, 13 Drawing Sheets
